UNITED STATES PATENT OFFICE

WILLIAM N. BOOTH, OF DETROIT, MICHIGAN, ASSIGNOR TO KELSEY-HAYES WHEEL CORPORATION, OF DETROIT, MICHIGAN, A CORPORATION OF NEW YORK

APPARATUS FOR FORMING CUP-SHAPED MEMBERS

Application filed May 2, 1927. Serial No. 188,340.

The invention relates to the manufacture of cup-shaped members and refers particularly to the apparatus for forming cup-shaped members. One of the objects of the invention is to so construct the apparatus that the cup-shaped members are expanded by liquid therewithin. Another object is to construct the apparatus with relatively movable die sections which determine in one position the contour of the cup-shaped members and which also permit of the removal of the cup-shaped members after being formed. Further objects of the invention reside in the novel features of construction and combinations and arrangements of parts as more fully hereinafter set forth.

In the drawings:—

Figures 1 and 2 are vertical median sections through an apparatus embodying my invention;

Figures 3 and 4 are cross sections respectively on the lines 3—3 and 4—4 of Figure 2.

The apparatus herewith shown is designed particularly to form the front sections of wire wheel hub shells and has the stationary die shoe 1 within which the die holder 2 is vertically slidable. For maintaining the base of the die holder normally spaced above the base of the die shoe, I have provided the rubber pad 3 which is located below the die shoe and the vertical rods 4 extending through the base of the die shoe and abutting at their lower ends the pad and at their upper ends the base of the die holder. 5 is the sectional die comprising the annular series of die sections 6 having outer inclined faces 7 for slidably engaging downwardly and inwardly inclined inner faces 8 upon the die holder 2. These die sections have to operating horizontal wedge-shaped inner ends 9 each having an inner face corresponding to the desired completed contour of the upper part of the cup-shaped member 10. When these die sections are in their lowermost positions, as determined by the stops 11 upon the base of the die holder 2 and engageable with the lower ends of the die sections the inner ends of the die sections form a continuous die with a continuous inner face. 12 is a second die supported

upon the base of the die shoe 1 and concentrically of the sectional die 5, this second die being adapted to extend upwardly within the sectional die and having an upper face corresponding to the contour of the remaining lower part of the cup-shaped member.

The cup-shaped member 10 when placed within the apparatus has, as shown in Figure 1, the bottom 13, the main cylindrical portion 14 connecting into the bottom, the outwardly and upwardly annular flared portion 15 connecting into the main cylindrical portion and the enlarged cylindrical portion 16 connecting into the flared portion. The die sections 6 at this time are held in elevated position and separated from each other by means of the pad 3 acting through the rods 4 and the flared portion 15 of the cup-shaped member engages and is supported by the correspondingly flared shoulders 17 upon the die sections. In the present instance the cup-shaped member when placed within the apparatus is filled with a predetermined amount of liquid such as oil, this amount being sufficient to expand the cup-shaped member against the die sections 6 and die 12.

18 is a holder suitably secured to a vertically reciprocable ram of a press. 19 are pins carried by the holder and vertically reciprocable relative thereto, these pins being yieldably forced downwardly relative to the holder by the coil springs 20. The pins are so located that there is one pin engageable with the upper end of each die section 6. As shown, each pin is slidably mounted in the bushing 21 secured to the holder, this bushing projecting downwardly below the holder and having the diametrically opposite slots 22 terminating short of the lower end of the bushing and engageable by the ends of the transverse pin 23 extending through the pin 19. The bushing also receives a coil spring 20. 24 is a plunger secured to the holder 18 and having the main cylindrical portion 25 for fitting the enlarged cylindrical portion 16 of the cup-shaped member, the tapered annular shoulder 26 for fitting the flared portion 15 of the cup-shaped member and the reduced cylin-

drical portion 27 for fitting the main cylindrical portion 14 of the cup-shaped member, as shown in Figure 2 of the drawings, the lower portion 28 of the punch is adapted to engage the bottom 13 of the cup-shaped member and to cooperate with the die 12 to serve the central portion of the bottom from the remaining part of the cup and form the hub cap hole.

10 In operation and with the parts as shown in Figure 1, downward movement of the ram and the holder 18 first carries the die sections 6 downwardly to their lowermost positions, at which time the cup-shaped member 10 is also carried downwardly. The 15 piercing portion 28 of the punch is also lowered at this time into the cup-shaped member. Then upon continued downward movement of the ram and holder the reduced 20 cylindrical portion 27 of the plunger 24 is brought into engagement with the upper part of the main cylindrical portion 14 of the cup-shaped member, and as it is lowered compels the liquid within the cup-shaped 25 member to move outwardly against the inner face of the lower part of the cup-shaped member to expand the same against the die sections 6 and die 12. Then the lower end of the plunger 24 contacts with the bottom 30 of the cup-shaped member and severs the central portion thereof. This central portion however, is not completely removed from the remaining part of the bottom so that the liquid can escape. The cup-shaped 35 member is now completely fashioned and may be removed and the central portion of its bottom knocked out.

For the purpose of facilitating the removal of the cup-shaped member, I have 40 provided the knock out pin 29 which extends axially through the die 12 and is provided at its upper end with the knock out collar 30 engageable with the central portion of the bottom of the cup-shaped member. The knock out pin 29 is actuated by 45 the ram upon its upward movement by suitable means such as the pull bars 31 connected to the ram and the cross bar 32 connected to the pull bars and knock out pin. 50 As a result, upward movement of the ram first permits the die sections 6 to move upwardly under the influence of the pad 3. Then the knock out pin is pulled upwardly to raise the cup-shaped member which in 55 turn slightly raises the die sections to provide sufficient clearance for the cup-shaped member to pass upwardly therethrough. After the cup-shaped member has passed upwardly therethrough these die sections 60 then gravitate back to their positions determined by the pad 3 and the apparatus is now ready to receive another cup-shaped member.

What I claim as my invention is:

65 1. In an apparatus for forming cup-

shaped members, the combination with a die for receiving a cup-shaped member, of means engageable within said cup-shaped member for forcing liquid outwardly thereagainst to expand the same, and means for shearing a portion from the bottom of the cup-shaped member. 70

2. In an apparatus for forming cup-shaped members, the combination with a die for receiving a cup-shaped member, of means engageable within said cup-shaped member for forcing liquid outwardly thereagainst to expand the same, and means actuated by said first-mentioned means for subsequently severing a portion from the bottom of the cup-shaped member. 75 80

3. In an apparatus for forming cup-shaped members, the combination with a die for receiving a cup-shaped member, of a plunger engageable within the cup-shaped member for forcing liquid outwardly thereagainst to expand the same, said plunger also being operable to shear a portion from the bottom of the cup-shaped member. 85

4. In an apparatus for forming cup-shaped members, the combination with a die for receiving a cup-shaped member, of a plunger engageable within the cup-shaped member for forcing liquid outwardly thereagainst to expand the same, and for shearing a portion from the bottom of the cup-shaped member. 90 95

5. In an apparatus for forming cup-shaped members, the combination with a die couple comprising a movable sectional die, the sections of which constitute a part of the whole of the contour of the cup-shaped member, a second die forming a wall corresponding to the remaining part of the desired contour of the completed cup-shaped member, means engageable within the cup-shaped member for forcing liquid outwardly thereagainst to expand the same against said dies, and means cooperating with said second die to shear a portion from the bottom of the cup-shaped member. 100 105 110

6. In an apparatus for forming cup-shaped members, the combination with a die couple comprising a movable sectional die, the sections of which constitute a continuous wall corresponding to part of the desired contour of the completed cup-shaped member, of a holder movable toward and away from said die, means carried by said holder for yieldably moving said sections to a position forming a continuous wall, and means carried by said holder for subsequently forcing liquid outwardly against the cup-shaped member to expand the same against said sections. 115 120 125

7. In an apparatus for forming cup-shaped members, the combination with a die couple comprising a movable sectional die, the sections of which constitute a continuous wall corresponding to part of the desired 130

contour of the completed cup-shaped member, of a reciprocable holder movable toward and away from said sections, means carried by said holder including a spring 5 pressed member for moving said sections to a position forming a continuous wall upon movement of said holder toward said sections, a plunger carried by said holder and engageable within the cup-shaped member for forcing liquid outwardly thereagainst to expand the same against said sections when in a position forming a continuous wall, and means actuated by said holder for ejecting the cup-shaped member and thereby moving 10 said sections in the opposite direction upon return movement of said holder.

8. In an apparatus for forming cup-shaped members, the combination with a sectional die for receiving a cup-shaped 20 member, of a reciprocable plunger movable in one direction for forcing liquid outwardly against the walls of said cup-shaped member to expand the same against the walls of said die, and means operated by said plunger during its movement in the opposite direction for moving the sections of the die away from the cup-shaped member and for automatically ejecting the cup-shaped member from the die.

30 9. In an apparatus for forming cup-shaped members, the combination with a die couple comprising a movable sectional die, the sections of which constitute a part of the whole of the contour of a cup-shaped member, and a second die forming the remaining part of the desired contour of the completed cup-shaped member, an injector member and a plunger operable when moved in one direction for forcing liquid outwardly against 40 the cup-shaped member to expand the same against said dies and operable when moved in the opposite direction to actuate said injector member for moving the sections of the sectional die away from the cup-shaped member and for ejecting the cup-shaped member from the sectional die.

10. In an apparatus for forming cup-shaped members, the combination with a die couple comprising a movable sectional die, the sections of which constitute a continuous side wall corresponding to part of the desired contour of the completed cup-shaped member, and a second die forming a bottom wall of the cup-shaped member, an ejector 50 member extending through the second die and engageable with the bottom wall of the cup-shaped member, and a reciprocable plunger movable in one direction for forcing liquid outwardly against the cup-shaped member to expand the same against said dies and operable when moved in the opposite direction to effect a corresponding movement of the ejector member for moving the 55 sections of the sectional die away from the

cup-shaped member and for ejecting the cup-shaped member from the sectional die.

11. In an apparatus for forming cup-shaped members, the combination with a die couple comprising a movable section die, the 60 sections of said die capable of movement relative to each other and when in operative position constitute a part of the whole of the contour of a cup-shaped member and a second die forming the remaining part of the desired contour of the completed cup-shaped member, and means for forcing liquid outwardly to expand the cup-shaped member against said dies.

12. In an apparatus for forming cup-shaped members, the combination with die means comprising relatively movable sections cooperating with each other in one position to form a part of the contour of the cup-shaped members, of means including a plunger for forcing liquid outwardly thereagainst to expand the same, and means operable prior to expansion of the cup-shaped member by the plunger for automatically moving the sections to operative position.

In testimony whereof I affix my signature:
WILLIAM N. BOOTH.
